UNITED STATES PATENT OFFICE

ALBERT BOUEKE, OF BREMEN, GERMANY

ARCH SUPPORTING INSOLE

Application filed May 8, 1930, Serial No. 450,667, and in Germany May 14, 1929.

This invention consists of an insole made of sheet metal for preventing or avoiding kinetic foot troubles caused by weak insteps.

The known insoles, particularly those made of sheet metal, effect owing to their curvature only a supporting or raising of the inner foot arch. The invention sets out to produce an insole which, whilst at the same time relieving the foot arch, effects an alteration of the position of the flat foot and at the same time, by ordinary bending with the hand, can be easily shaped to any foot to be loosely inserted into the shoe.

The invention consists in a base plate that extends from the part adapted to the foot arch to a narrow surface extension on the inner foot edge towards the front and towards the rear, and that it is provided on the under side of these extensions in front of and behind the actual foot arch with a known supporting means of suitable shape (block, supporting pad or the like) for raising the foot at these points.

Owing to this construction the flat foot is slightly raised at two points, in front of and behind the actual inner arch respectively, by the means of the insole indicated, and consequently the peculiar manner of the weight transmission from the shank to the foot, when standing and walking, is tipped slightly towards the outer side and towards the rear, so that the excessive weight, which causes the sinking of the foot is transferred to the rear from the inner part of the foot to the foot bearing surface proper (heel-outer edge-outer forepart of the foot). The relative relieving and distending of the inner foot part, caused by this alteration of position of the flat foot, enables the use of a base plate, made of sheet metal bendable with the hands, without any fastening, guide or the like, on a second supporting plate, in the shoe, whilst retaining a suitable curvature, which on a continuation of the overloading of the inner part of the flat foot is not possible, without the bend of the foot and of the base plate being trodden flat.

By means of the flexible base plate the plate can be bent by the wearer himself, according to the requirements of his foot, and

the plate can be adapted to the foot sole without producing points of pressure on the foot sole.

An embodiment of the invention is illustrated by way of example in the accompanying drawings in which:

Fig. 1 shows in side elevation the insole loaded by a foot.

Fig. 2 is a top plan view of the insole.

Fig. 3 is a cross section through the insole.

The insole consists of a base plate *c* of flexible sheet metal, merely covered with the leather inner sole *a*.

The base plate *c* extends, from the centre and wider part fitted to the foot arch, towards the front and towards the rear in a narrow front surface extension *c'* and rear surface extension *c''* (Fig. 2). On the under side of these two extensions *c'* and *c''* a supporting means of suitable shape of felt, rubber or the like, is fitted like a block *d* (Fig. 2) in front of and behind the foot arch respectively. Under certain circumstances however only one of such supporting means may be used, namely on the under side of the front extension *c'*. By adjusting the blocks *d* at a certain height, under certain conditions the two blocks at different heights, the base plate *c* is brought into a position inclining downwardly towards the outer side and towards the rear (Fig. 3).

The base plate *c*, which consists in known manner of any suitable sheet metal bendable by hand, is used in the shape and arrangement described as an unlimitedly bendable, independent plate without any fastening, guide or the like (on a second supporting plate, in the shoe), the usual covering inner leather sole being immaterial.

The operation of the insole is as follows:

Owing to the supporting means, adjustable to a certain height, the foot is slightly raised at these points in front of and behind the arch respectively and to a certain extent relieved, in that the main joint of the tarsus and of the metatarsus is slightly shifted and thereby slightly tipped outwardly and rearwardly.

By this means, in the case of flat foot, in conjunction with the peculiarity of the con-

nection or load transmission from the shank to the foot, which is caused by the particular construction of the skeleton of the foot, a displacement of load from the inner longitudinal arch of the foot to the natural sole loading surface is effected. The longitudinal arch is thereby relatively relieved and distended.

5 The base plate of sheet metal bendable in suitable manner by hand is inserted, owing to 10 the action of the insole above described, in curved shape into the shoe without further fastening, guiding or the like, and thus used.

As the base plate is in no way limited when 15 the plate is inserted and when the wearer is standing or walking, it clings merely to the sole of the foot according to the actual conditions of the foot arch, without causing pressure points and the like. According to the 20 entire arrangement of the insole the base plate no longer serves for raising or as lifting support of the foot arch proper.

I claim:

A shoe insole including an arch support comprising a metallic plate arched between 25 its ends, and the said ends being straight, the said metallic plate being broad at the apex of the arch and gradually diminishing in width throughout its curved portion until it merges with the straight end portions, and 30 one edge of the plate being concentric with the edge of the sole of the shoe to which it is fitted, and elastic supports on which the straight ends of the plate are supported.

In testimony whereof I affix my signature.

35 ALBERT BOUEKE.
